Primary Examiner — Kevin K Rudzinski*Assistant Examiner* — Clare Ann Gannon(74) *Attorney, Agent, or Firm* — Simpson & Simpson, PLLC(57) **CLAIM**

The ornamental design for a shoe mat, as shown and described.

DESCRIPTION

FIG. 1 is a front perspective view of the shoe mat, showing the new design;

FIG. 2 is a front elevational view thereof;

FIG. 3 is a right side elevational view thereof;

FIG. 4 is a back elevational view thereof;

FIG. 5 is a left side elevational view thereof;

FIG. 6 is a top plan view thereof;

FIG. 7 is a bottom plan view thereof;

FIG. 8 is a front perspective view thereof, shown in an alternate configuration; and,

FIG. 9 is a front perspective view thereof, shown in an alternate configuration.

Broken lines depict portions of the article that form no part of the claimed design.

1 Claim, 9 Drawing Sheets(56)
